(74) Attorney, Agent, or Firm — Legends Law Group, PLLC; Stephen H. Bean, Esq.(57) CLAIM

I claim the ornamental design for the floor grate insert assembly, as shown and described.

DESCRIPTION

FIG. 1 is a perspective view from above;

FIG. 2 is a perspective view from below;

FIG. 3 is a top view;

FIG. 4 is an end view;

FIG. 5 is a bottom view;

FIG. 6 is a side view; and,

FIG. 7 is a perspective view exploded, thereof.

The floor grate insert assembly is shown with symbolic breaks in its length in FIGS. 1-3 and 5-7. The appearance of any portion of the article between the break lines forms no part of the claim.1 Claim, 4 Drawing SheetsFig. 1
